R. E. REARDON

FLY SWATTER TOY FIREARM

Filed June 1, 1922

Patented Feb. 17, 1925.

1,526,505

UNITED STATES PATENT OFFICE.

ROBERT E. REARDON, OF COLUMBIA, PENNSYLVANIA.

FLY SWATTER TOY FIREARM.

Application filed June 1, 1922. Serial No. 565,027.

To all whom it may concern:

Be it known that I, ROBERT EDWIN REARDON, a subject of the King of Great Britain, residing in the town of Columbia, county of 5 Lancaster and State of Pennsylvania, United States of America, have invented a new and useful Fly Swatter Toy Firearm, of which the following is a specification.

My invention relates to improvements in 10 toy firearms and its object is to provide means by which marksmanship may be practiced on flies by a device which may be described as a fly swatter toy gun.

My improvement is herein presented in 15 the form of a toy gun having a spring projectable, trigger released barrel member carrying on its muzzle end a resiliently mounted wire netting disk, through or over which barrel member and disk aim may be taken at a fly and the disk swatter then projected against it.

My invention is illustrated in the accompanying drawing in which:

Figure 1 is a side elevation of my fly 25 swatter toy gun showing the parts thereof in normal position with a part broken away;

Figure 2 is a side elevation showing an 30 alternative, cheaper form of construction of my fly swatter toy gun, with parts in normal position and with a part broken away.

Similar numerals refer to similar parts throughout the two views.

The preferable form of construction of 35 my toy gun shown in Figure 1 is illustrated in a convenient method of manufacture.

The stock A has slidingly mounted longitudinally on its barrel portion A¹ by means 40 of retaining and guiding screw eyes B and C, a projectable barrel member D which has affixed to its flanged muzzle end D¹, by means of a resilient rubber neck E which by interior groove E¹ engages same, a disk 45 H of wire netting mounted on a ring G, secured in the muzzle end of the rubber neck E by means of an interior groove E² therein. On the butt end D² of the barrel member D is mounted fixedly a cylinder F which 50 has at its forward end a radial flange F¹ which serves as a finger grip for drawing back the barrel member D to cocked position, and at its rearward end a radial flange F² which is a means of cocking engagement 55 with a nose L² of a resilient trigger L mounted by its rear end L¹ on the breech

A² of the stock A and having a finger arm L³ extending downwardly from its nose L² through a slot A³ in stock A to a position below same suitable for finger pressure. 60 The rear end L¹ of trigger member L is secured to the breech A² of stock A by a screw eye I passed through a hole L⁴ in it. The screw eye I is set in alignment as to eye center with screw eyes B and C and 65 secured in its eye, by soldering or otherwise, by its breech end J¹, is a sighting and guiding barrel J, fixedly mounted centrally of screw eye I and extending at a right angle thereto and horizontally therefrom muzzleward, through projectable barrel member D and therein through screw eyes B and C, in coaxial alignment therewith, or as close an approximation of such alignment as commercial construction will 70 permit. This arrangement of simple parts gives a fixed sighting barrel or open ended tube on which a projectable barrel is mounted and freely slidable within stop limits. Spring action, for cheap construction, is obtained by use of rubber bands. 75 A rubber band K, of sufficient strength to impart the necessary projectile force to kill a fly, is secured to screw eye B at the muzzle end A¹ of stock A, preferably by simply looping over same, and stretched with slight tension and secured to radial flange F¹ on barrel member D, by passing through a transverse hole F³ in flange F¹ lower half and looping over a stud F⁴ formed on rear face 80 of said flange. A weaker rubber band M, which constitutes a return spring functioning normally by holding barrel member D partially retracted, against tension of spring band K, is secured to barrel member D by 85 being looped over a hook stud F⁵ formed on the rear face of the upper half of flange F¹, and stretched therefrom to and looped over screw eye I and under rear end L¹ of trigger member L. 90

In the alternative construction of my fly swatter toy firearm shown in Figure 2, the stock A has a longitudinal groove A⁴ in its barrel portion A¹ and the retaining and mounting screw eyes B and C are replaced 105 by a flanged sheet metal cylinder N, the flange N¹ forming a longitudinal fin which is set in vertical slot A⁵ in the barrel section A¹ of stock A and held therein by a transverse nail O, the cylinder N lying in the 110 groove A⁴ of stock A. The sighting guide barrel J is dispensed with in this con-

struction and projectable barrel D when retracted is guided by the groove A⁴ into a sheet metal hood P set in same which replaces the screw eye I of Figure 1. The said hood P is secured in position in alignment with the cylinder muzzle bearing N by being clamped in the slot A³ of stock A by insertion in said slot A³ between the walls P¹ of the hood P of the forward end A⁶ of 10 shoulder section A⁷ of the stock A, the barrel section A¹ of which is jointed to shoulder section A⁷ at this point by transverse nails Q, Q, the stock A being made in two sections for economy and ease of manufacture. The 15 rear end or arm L¹ of trigger L in this construction is secured by a nail R to the tongue A⁶ of the shoulder section A⁷ of stock A and lies in the slot A³ below the horizontal plane of the groove A⁴ in which 20 barrel member D travels. A single rubber band K furnishes the spring motive force for projecting the barrel member D forwardly. It is looped over the cylinder N at the muzzle end of gun, into a transverse 25 slot A⁸ in stock barrel section A¹, and drawn back to radial flange F¹ of inverted barrel member D and secured to said flange F¹ as in the construction of my gun shown in Figure 2.

30 The operation of my fly swatter toy firearm is effected by gripping the projectable barrel member D by its flange F¹ and drawing it back until its flange F² engages the nose L² of trigger L. Aim is then taken 35 through the barrel member D and sighting barrel J or hood P, according to which construction of my gun is used, at a fly within striking distance. The finger arm L³ of the trigger being then pressed, the nose L² of 40 same is depressed by depression of the resilient arm L⁵ and the projectable member D is released by disengagement of its flange F² from trigger nose L² and shoots forward by contractile action of the spring rubber 45 band K, then returning in my preferable construction as per Figure 1, by contractile action of the spring rubber return band M.

While I have shown and described one form of my fly swatter toy firearm and one modification thereof, for illustrative purposes, it is to be understood that a number of modifications and deviations from the illustrated embodiment may be made without departing from the spirit of the invention.

I claim:

1. In a toy firearm, means for aiming a fly swatter projectile part having a resilient rubber head bearing a disk of wire netting, spring tubular aperture means for projecting said fly swatter projectile part, and trigger means for releasing said spring projecting means. 55
2. In a toy firearm, a fly swatting projectile provided with an opening through the center of which the target is visible. 60
3. In a toy firearm, a fly swatting projectile provided with an opening through the center of which the target is visible and spring means for projecting said projectile. 65
4. In a toy firearm, a transparent fly swatter projectile provided with an opening through the center of which the target is visible, means for projecting the said projectile and trigger means for releasing said projecting means. 70
5. In a toy firearm, a projectile member with a transparent fly swatter head and continuously open tubular body. 75
6. In a toy firearm, a fly swatting projectile through the longitudinal axis of which aim may be taken at a target. 80
7. In a toy firearm, a barrel through which aim may be taken at a target and a projectile provided with an opening through which aim may be taken at a target. 85
8. In a toy firearm, a fly swatter and spring means for longitudinally projecting and retracting said fly swatter. 90
9. In a toy firearm, a hollow rod projectile member, axially of which a target may be aimed at, and spring means for projecting and retracting said projectile member. 95

ROBERT E. REARDON.
